(57) **CLAIM**

The ornamental design for a multi-function cutter and grater, as shown and described.

DESCRIPTION

FIG. 1 is a top plan view of a multi-function cutter and grater showing my new design, with a cover.

FIG. 2 is a front perspective view of the cutter and grater of FIG. 1, wherein the rear perspective view is a mirror image thereof;

FIG. 3 is a right side perspective view of the cutter and grater of FIG. 1;

FIG. 4 is a right bottom perspective view of the cutter and grater of FIG. 1;

FIG. 5 is a left side elevational view of the cutter and grater of FIG. 1;

FIG. 6 bottom plan view of the cutter and grater of FIG. 1; FIG. 7 is a right side elevational view of the cutter and grater of FIG. 1;

FIG. 8 is a right side perspective view of the cutter and grater of FIG. 1 in which the cover is shown in open position;

FIG. 9 is a right bottom perspective view of the cutter and grater of FIG. 1 which includes a grate screen;

FIG. 10 is a bottom plan view of the cutter and grater of FIG. 9;

FIG. 11 is a right side perspective view of the cutter and grater of FIG. 1 shown in one operable position as attached to a rim of a round bowl;

FIG. 12 is a right bottom perspective view of the cutter and grater of FIG. 11;

FIG. 13 is a right side perspective view of the cutter and grater with the cover being removed;

FIG. 14 is a top plan view of the cutter and grater of FIG. 13; FIG. 15 is a right front perspective view of the cutter and grater of FIG. 13;

FIG. 16 is a front perspective view of the cutter and grater of FIG. 13;

FIG. 17 is a right side perspective view of the cutter and grater of FIG. 13 shown in one operable position as attached to a rim of a round bowl;

FIG. 18 is a front perspective view of the cutter and grater of FIG. 17;

FIG. 19 is a front perspective view of the cutter and grater of FIG. 13; and,

FIG. 20 is a front perspective view of the cutter and grater of FIG. 17.

The broken lines contained in the Figures are for illustrative purposes only and form no part of the claimed design.
